CLAIM

The ornamental design for a deadlift bar, as shown and described.

DESCRIPTION

FIG. 1 is a front, right, top perspective view of a deadlift bar showing my new design;

FIG. 2 is a back, left, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the bounded area 9 of FIG. 2; and,

FIG. 10 is an enlarged view of the bounded area 10 of FIG. 3.

The broken lines shown on the drawings depict portions of the deadlift bar that form no part of the claimed design. The dot-dash lines depict the enlarged view boundaries that do not form part of the claimed design.

1 Claim, 10 Drawing Sheets
